UNITED STATES PATENT OFFICE.

MILES A. SANDERS, OF IUKA, ILLINOIS.

PACKAGE-TIE.

1,155,961.

Specification of Letters Patent.

Patented Oct. 5, 1915.

Application filed February 15, 1915. Serial No. 8,257.

To all whom it may concern:

Be it known that I, MILES A. SANDERS, a citizen of the United States, residing at Iuka, in the county of Marion and State of Illinois, have invented certain new and useful Improvements in Package-Ties; and I do hereby declare the following to be a full, clear, and exact description of the invention, such as will enable others skilled in the art 10 to which it appertains to make and use the same.

This invention has for its object to provide a simple and efficient package tie or cord holder for reliably holding a cord in 15 position about a package.

Another object is the provision of a package tie formed entirely of a single piece of sheet metal anchored at one end to a flexible member or cord and including means adapted to reliably secure the opposite or free end of the cord.

With these and other objects in view, the invention consists in the novel construction, arrangement and formation of parts as will 25 be hereinafter specifically described, claimed and illustrated in the accompanying drawing in which:

Figure 1 represents a top plan view of the package tie applied to use. Fig. 2 represents a perspective view thereof.

Referring to the drawing in detail, wherein similar reference numerals designate corresponding parts throughout the several views, the numeral 5 indicates the body of 35 the holder or tie which is formed adjacent one end with a pair of inwardly directed transverse slits 6, the portion of the body outwardly of the slits being bent inwardly, as indicated at 7, to securely clamp one end 40 of a securing cord 8. The body 5 is bent on a line approximately at forty-five degrees to

the longitudinal center thereof to provide the obliquely disposed cord-receiving groove 9. The portion 10 of the package tie or cord holder is disposed above and in spaced relation to the body 5 and the end opposite the clamping members 7 is reduced, as indicated at 11, and bent back upon the intermediate member 10 on a line disposed parallel with the longitudinal center of the body 5. The 50 bight portion of the superposed reduced end 11 is formed with an integral pointed tooth 12.

In use, the tie is placed upon the package 13 and the cord or other flexible member 8 55 is looped longitudinally about the package and is disposed between the body 5 and the intermediate member 10 and is seated within the groove 9. The cord is subsequently looped transversely about the package and 60 the free end portion thereof is engaged beneath the superposed member 11. The pointed tooth 12 reliably holds the cord against longitudinal movement under the member 11 and thus prevents the cord from 65 loosening.

What I claim is:

A package tie including a relatively flat body, a cord secured to one end of said body, the opposite end of said body being bent 70 on an oblique line to define an intermediate member, a reduced end on said body bent over the intermediate member, and a tooth formed in the bight portion of the reduced end. 75

In testimony whereof I affix my signature in presence of two witnesses.

MILES A. SANDERS.
